United States Patent

Des. 235,946
Patented July 22, 1975

235,946

SEAT

Gordon L. Duern and Donald S. Griffin, Kitchener,
Ontario, Canada, assignors to Electrohome Limited,
Kitchener, Ontario, Canada

Continuation of abandoned design applications Ser. No.
127,083, Mar. 22, 1971, and Ser. No. 128,646, Mar. 26,
1971. This application Jan. 15, 1973, Ser. No. 323,722

Term of patent 14 years

Int. Cl. D6—01

U.S. Cl. D6—47

FIG. 1

FIG. 2

FIG. 3

FIG. 4

FIG. 1 is a front perspective view of a seat showing our design in the form of a chair.

FIG. 2 is a rear perspective view thereof.

FIG. 3 is a perspective view of a modified version of the seat of FIG. 1 shown in the form of a love seat.

FIG. 4 is another perspective thereof wherein the seat has been rotated about 90° from the viewpoint in FIG. 3.

This application is a continuation of applications Ser. No. D. 127,083, filed Mar. 22, 1971, and Ser. No. D. 128,646, filed Mar. 26, 1971, and now abandoned.

We claim:

The ornamental design for a seat, as shown and described.
